STORAGE TANK

Karl M. Speig, Pacoima, Calif.

Application August 26, 1949, Serial No. 112,467

7 Claims.

(Cl. 169—4)

1

This invention relates to a storage tank and more particularly to tanks designed for the storage of inflammable materials and incorporating cooling and fire control structure.

It is intended by this instant invention to provide a fireproofed storage tank for inflammable material which may be used in open fields or indoors and by virtue of which the inflammable materials stored therein may be maintained in a cool condition safe from any fire which may be raging therearound.

It is among the objects of the invention to provide new and improved means for cooling and fireproofing, both internally and externally, an inflammable-carrying storage tank.

It is also among the objects of the invention to provide an improved double wall storage tank construction in combination with a cooling fluid intended to be retained therein and in case of need to be circulated, overflowed, and distributed thereabout.

Another object of the invention is to provide new and improved automatic fire extinguishing construction for tank walls and other structures such as houses, buildings and the like.

This invention contemplates, in addition, the prevention of explosion within storage tanks of single or doubled walled construction, preferably the latter, with new and improved provision for relief of internal stresses due to heat expansion. It likewise contemplates improvements over prior art structures heretofore intended to accomplish generally similar purposes.

In addition to the above recited objects it is intended by the instant invention to provide improvements over prior art structures heretofore intended to accomplish generally similar purposes and in this connection, the invention consists in the construction, arrangement and combination of the various parts of the device whereby the objects contemplated are attained, as hereinafter set forth, pointed out in the appended claims, and illustrated in the accompanying drawings.

In the drawings:

Figure 1 is a vertical sectional view of an outdoor storage tank embodying this invention;

Figure 2 is a top view thereof, parts being cut away;

Figure 3 is a vertical sectional view of an inside storage tank embodying this invention; and

Figure 4 is a top view thereof.

Referring more particularly to the drawings, and specifically Figures 1 and 2 thereof, an outdoor storage tank 20 located as in a field 21, generally comprises an inner tank 22 and an outer tank 23, both of which may be mounted as upon a cement slab 24 and preferably braced and secured together as by braces 25.

The outer tank 23 may be fitted as with a conical roof 26 formed as with an access hole 27, normally covered, and spaced depending flanges 28 welded or otherwise secured thereto as at 29 along

2

circumferentially spaced points along the upper rim 30 of such tank 23.

Such upper rim 30 of the outer tank may be smooth or it may be provided with a plurality of ridges, notches or the like 31, but, whether formed with notches 31 or not, is preferably spaced downwardly from the roof 26 providing a substantially continuous annular opening under said roof and above the rim of said tank as indicated at 33, except for the flanges 28 at which the roof is secured, either permanently or removably, to the outer tank.

A drain valve 34 may communicate, as through an outlet 35, with the interior of the outer tank 23, i. e., with the space 36, preferably of annular form, the tanks being customarily cylindrical, between the inner tank 22 and the outer tank 23. On the outside of the tank a ladder 38 may be provided.

20 The inner tank 22, unlike the outer tank 23 which is entirely devoid of a top other than the roof 26, is closed at its top 40 except for the optional provision of an access opening 41 closed in any suitable watertight fashion by an access door 42 thereover.

A vent pipe 43 may be threadedly secured as at 44 to the top of the tank 22 terminating in a stand pipe portion 44 spaced somewhat away from the storage tank 20 and provided as with a vent cap 45.

Both the inner tank 22 and the outer tank 23 are firmly secured, as by angles 46 embedded in the concrete slab, to said concrete slab in a watertight manner known to those skilled in the art, or 35 either or both such inner and outer tanks may be provided with separate or common bottoms, making of either or both of them integral closed containers.

The concrete slab 24 may likewise be formed 40 with a sump 48 as of annular shape including drain pipes 49 communicating therewith. A filling pipe 50 communicates with the interior 51 of the inner tank 22 for filling such inner tank with a combustible fluid, as gas, gasoline, oil, natural gas or the like. A water supply pipe 52 communicates as at 53 with the annular space 36 between the tanks.

The supply pipe 52 may be controlled by a manually operable valve 54 preferably at a position remote from the storage tank 20, but the valve 54 is preferably stationed relatively proximate to the storage tanks and of an automatic character. Thus it may be operated either from a float similar to a toilet control valve at the 55 top of the outer tank 23 or by a fire or heat operated valve adapted to be open when subjected to the extreme heat of a fire. In either event, the supply pipe 52 is intended to maintain a constant water supply in the annular space 36 substantially to the full extent of the capacity of the outer tank.

Inasmuch as such outer tank extends above the

inner tank such inner tank will be constantly and totally immersed in the water contained within such annular space. If a fire should envelop the storage tank, the valve 54 would be opened either manual or automatically as aforesaid, thereby overflowing the rim 30 of the outer tank and flowing in spaced rivulets or as a continuous falls around and over the outside of the tank 23.

Water will also spread over the field 21 around the tank, serving to keeping burning substances away or cooling and extinguishing them while simultaneously protecting and maintaining a low temperature in the contents of the inner tank 22.

It should be noted that the fluid, preferably water, contained in the annular space 36 between the tanks would normally maintain a cool condition within the inner tank 22 merely by evaporation but such cooling effect is insured and assisted by the continual circulation of fresh cold water from the supply pipe 52. The positioning of the filling pipe 50 is such that if the normal flow therein be reversed, it, together with the drain or sump pipe 49, may remove the combustible material within the inner tank to a place remote from the fire if desired.

In the form of the storage tank illustrated in Figures 3 and 4 a tank generally designated at 100 comprises an outer tank 101 having an open top 102 and a closed bottom 103 all supported above a floor 104 as of a garage by means of steel legs 106 held on or in the floor in any conventional manner.

An inner tank 108 is supported as upon legs 109 on the bottom 103 of the outer tank to provide a space between the inner and outer tank for the circulation of water 110 around and over the inner tank 144 when delivered as through a supply pipe 111.

An outlet pipe 112 communicates internally as at 113 with the interior 114 of the inner tank, the outlet flow from the inner tank being governed preferably by a conventional spring-acting delivery nozzle 115 connected as to a flexible hose 116.

The inner tank 108 is adapted to be filled as by supply garage pipe 118 projecting outwardly through a wall 120 of an enclosure or building and encased as within an asbestos or other fire-resistant coating 121.

A drain valve 125 may be provided for the outer tank 101 in the bottom 103 thereof, and the automatic valve 126 may control the water supply in the pipe 111 normally maintaining the outer tank 101 full of water to the brim 102 thereof.

In the modified form of the invention, gasoline or the like is poured into the inner tank 108 through the plugged opening 130 outside of the wall 120 and is removed from such inner tank by pipe 112, hose 116, and nozzle 115.

Water enters the outer tank filling the space between the outer tank and the inner tank through pipe 111 and the valve 126, maintaining the water supply in the outer tank around and over the inner tank.

In the event of a fire, a float 132 which is made of a material subject to destruction by fire or extreme heat such as a thin vinyl plastic is destroyed, ruptured or shriveled by the heat permitting the automatic valve 126 to open and supplying a continuous stream of fresh water around the inner tank 108. The incoming water continuously overflows the rim 102 of the larger

tank keeping the outside thereof cool and spreading over the floor 104.

The float 132, in the event of such destruction thereof, permits the lever 135 to be continuously overbalanced in a clockwise direction as shown in Figures 3 and 4, the long end 136 thereof inwardly of the fulcrum 137 being heavier than the shorter end 138. The valve 126 thereby remains continuously open for flooding purposes, inasmuch as the cable 139 pulls up on the handle 140 of the valve 126 to open the latter. Thus, when the float 132 is operative, the water level is kept at a given height above the inner tank 108, and when the float is destroyed, the outer tank 101 overflows.

The lever 140 of the valve 126 normally falls to horizontal, as shown in Fig. 3, in the closed position of the valve, and is opened by counter-clockwise movement under the influence of the cable 139 and lever 135.

The rim 102 may be notched in a similar manner to the rim of the first embodiment of Figures 1 and 2.

Tests of the instant invention have found that notwithstanding an oil fire or the like continuously played over and around the storage tank 20 or 100 a relatively slight circulation of water, as from the two pipes 52 or 111, maintains a temperature within the inner tank sufficiently low to prevent combustion of the most volatile forms of gasoline contained therein. A sufficient circulation of water will retain the inner tank at a temperature close to that of the incoming water notwithstanding the fire temperature.

Even if the water between the inner and outer tanks is brought to a boil by a cessation of the freshwater supply thereto, the inner tank, so long as it remains covered, will retain a temperature which does not exceed that of boiling water.

This invention features the provision of a new and improved storage tank construction for maintaining a cool temperature in an inner tank regardless of the external temperature of the outer tank. It likewise features a new and improved means by which the inner tank is constantly immersed in water or other cooling fluids, by which a fresh supply of cool water is automatically supplied for covering the inner tank in the event of a fire, and by an outer tank construction permitting boiling and overflow and escape of the water contained therein. A cooling, fire-extinguishing and anti-explosive effect is thereby created.

While I have herein shown and described my invention in what I have conceived to be the most practical and preferred embodiment, it is recognized that departures may be made therefrom within the scope of my invention, which is not to be limited to the details disclosed herein, for obvious modifications will occur to a person skilled in the art.

Having thus described my invention, what I claim as new and desire to secure by Letters Patent is:

1. A storage tank construction comprising a watertight outer container having an open top and a closed bottom and sides, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water com-

municating between the inner and outer tank including valve means for maintaining the water supply within the outer tank to a position approximately filling such outer tank and covering such inner tank with water, and whereby the outer tank may be constantly flooded by water to overflow its rim.

2. A storage tank construction comprising a watertight outer container having an open top and a closed bottom and sides, a roof over the outer tank spaced upwardly therefrom and defining an opening superadjacent the open top of the outer tank, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water communicating between the inner and outer tank including valve means for maintaining the water supply within the outer tank to a position approximately filling such outer tank and covering such inner tank with water, and whereby the outer tank may be constantly flooded by water to overflow its rim.

3. A storage tank construction comprising a watertight outer container having an open top and a closed bottom and sides, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water communicating between the inner and outer tank including automatic valve means for maintaining the water supply within the outer tank to a position approximately filling such outer tank and covering such inner tank with water, and whereby the outer tank may be constantly flooded by water to overflow its rim.

4. A storage tank construction comprising a watertight outer container having an open top and a closed bottom and sides, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water communicating between the inner and outer tank including automatic fire-destructible means on said automatic valve means designed for destruction by the relatively high temperature of a fire to open said automatic valve control means, valve means for maintaining the water supply within the outer tank to a position approximately filling such outer tank and covering such inner tank with water, and whereby the outer tank may be constantly flooded by water to overflow its rim.

5. A storage tank construction comprising a watertight outer container having an open top and a closed bottom and sides, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water communicating between the inner and outer tank including valve means for maintaining the water

supply within the outer tank to a position approximately filling such outer tank and covering such inner tank with water, whereby the outer tank may be constantly flooded by water to overflow its rim, and notch means on the rim of the outer tank whereby the overflowing water is directed in spaced rivulets down the outside of the outer tank for even distribution therearound.

6. A storage tank construction comprising a watertight outer container having an open top and a closed bottom and sides, an inner tank spaced inwardly and downwardly from the walls and open top of the outer tank, respectively, so that the inner tank is wholly contained within the outer tank whereby when the outer tank is completely filled with water the inner tank is entirely immersed in such water, water inlet means connected to a source of cool water communicating between the inner and outer tank including automatic fire-destructible means on said automatic valve means designed for destruction by the relatively high temperature of a fire to open said automatic valve control means, valve means for maintaining the water supply within the outer tank to a position approximately filling such outer tank and covering such inner tank with water, whereby the outer tank may be constantly flooded by water to overflow its rim, said automatic valve means comprising a float valve normally holding said valve closed when the water is at a predetermined level, said float valve comprising a fire-destructible material, destruction of which permits said valve to open.

7. A storage tank construction comprising a watertight outer container having an open top and a closed bottom and sides, a roof over the outer tank spaced upwardly therefrom and defining an opening superadjacent the open top of the outer tank, an inner tank spaced inwardly and downwardly from the walls and open top of the outer tank, respectively, so that the inner tank is wholly contained within the outer tank whereby when the outer tank is completely filled with water the inner tank is entirely immersed in such water, inlet means for combustible material to be stored within the inner tank, vent means for the inner tank, drainage means for the inner tank, water inlet means connected to a source of cool water communicating between the inner and outer tank including automatic fire-destructible means on said automatic valve means designed for destruction by the relatively high temperature of a fire to open said automatic valve control means, whereby the outer tank may be constantly flooded by water to overflow its rim, and notch means on the rim of the outer tank whereby the overflowing water is directed in spaced rivulets down the outside of the outer tank for even distribution therearound, said automatic valve means comprising a float valve normally holding said valve closed when the water is at a predetermined level, said float valve comprising a fire-destructible material, destruction of which permits said valve to open, said inner tank being supported above the bottom of the outer tank but below the rim thereof.
